UNITED STATES PATENT OFFICE.

FREDERICK I. JOHNSON, OF WARREN, RHODE ISLAND, ASSIGNOR TO MARY W. JOHNSON, OF WARREN, RHODE ISLAND.

WIRING-CONDUIT CAP.

1,382,510.

Specification of Letters Patent. Patented June 21, 1921.

Application filed July 18, 1919. Serial No. 311,746.

To all whom it may concern:

Be it known that I, FREDERICK I. JOHNSON, a citizen of the United States, and resident of Warren, in the county of Bristol 5 and State of Rhode Island, have invented certain new and useful Improvements in Wiring-Conduit Caps, of which the following is a specification.

This invention relates to weather caps 10 for protecting the ends of wire-receiving conduits through which electric wires are led into a building or the like, and the object of this invention is to provide such a conduit-end, cap or protector comprising a 15 substantially elbow-shaped body member having a rotatable coupling connected to one end thereof and an end guide member of insulating material connected to the opposite end thereof the joint between the body and 20 each of these ends being protected against the action of rain or snow by an overlapping skirt or flange portion.

With these and other objects in view, the invention consists of certain novel features 25 of construction, as will be more fully described, and particularly pointed out in the appended claims.

In the accompanying drawings:

Figure 1—is a side elevation illustrating 30 my improved protecting cap as applied to a horizontal conduit.

Fig. 2—is a sectional view of the body portion of the protecting member with the porcelain removed.

Fig. 3—is an end view of the body portion with the porcelain and coupling members removed.

Fig. 4—shows a different style of elbow member as connected to a vertically-disposed conduit.

Referring to the drawings, 10 designates the body member of my improved conduit end protector which is preferably formed of cast or molded metal and in substantially an 45 elbow-shape, that is the axes through the different openings are set at an angle to each other. The wire entering end of this cap or protector is provided with an annular flange 11 which is preferably of greater diameter 50 than the body portion thereof and the bottom face 12 of this flange provides an annular seat against which the inner face 13 of the porcelain or insulating end piece 14 rests.

This flange is provided with ears 15

tapped to receive one or more binding 55 screws 16.

It will be noted by this construction that the flange 11 as it is set to project in a downward direction, serves as a skirt to cover the joint between the porcelain end piece and 60 the body of the cap, so as to effectually prevent moisture from working through the joint into the body of the cap, which in winter time would be apt to freeze and in some cases crack the cap and possibly 65 destroy the insulation and short circuit the wires.

Near the opposite end of this protector or cap is provided an inwardly projecting flange 17, against the outer face of which 70 sets the end of the coupling member 18. This coupling member is threaded on its inner surface at 19 and its inner end is provided with an inwardly turned flange 20 corresponding to the inwardly turned flange 17 75 on the body portion, and a thimble or ferrule 21 of suitable, bendable material is provided having its opposite edges swaged over the two inturned flanges 17 and 20 to loosely connect this coupling member to the body 80 whereby the coupling member may be rotated to engage the threaded end of the conduit 22 without being obliged to rotate either the conduit or the cap thus greatly facilitating the connecting of these two members together. 85

I have shown and described the coupling as connected to the cap by a separate thimble, but any suitable means may be employed for connecting together these two members. 90

It is found in practice that where such a connection is made, that it is quite necessary to provide a skirt, flange or overhanging lip 23 to exclude the weather from this joint and protect the same by positively preventing 95 the entrance of either snow or rain through this joint.

Even with this overhanging skirt it is found that in some cases driving storms will work under the overhanging skirt and I 100 have, therefore, cut away this flange 23 at its bottom portion 24 so that any water which may work under the flange will run out through this opening and prevent the accumulation of water which might work back 105 through the joint.

In Figs. 1 to 3 inclusive I have shown a pair of ears and two binding screws ar-

ranged to retain the porcelain member in the cap, while in Fig. 4 I have shown a lip 25 which is adapted to engage one edge of the flange of the porcelain member while the opposite side of the porcelain member is retained by a single screw 26.

My improved construction of conduit end protector is very simple, practical and inexpensive and may be very readily applied to a 10 conduit, and at the same time is designed to effectually protect both the end of the conduit against the entrance of moisture, and thus prevent short circuiting of the wires, which might otherwise result from freezing.

15 The foregoing description is directed solely toward the construction illustrated, but I desire it to be understood that I reserve the privilege of resorting to all the mechanical changes to which the device is susceptible, the invention being defined and limited only by the terms of the appended 20 claims.

I claim:

1. A wiring conduit cap comprising a substantially 25 elbow-shaped body having a socket

at one end for receiving an insulating guide for the wires and an inwardly turned flange at its opposite or conduit receiving end, a coupling member connected to the inner edge of said flange by a swivel joint whereby 30 said body may be attached to the threaded end of a conduit without rotating either the body or the conduit, and a weather shielding flange on said body extending over the joint between it and said coupling. 35

2. A wiring conduit cap comprising a substantially elbow-shaped body having an annular out-turned flange for inclosing and providing a seat for a removable insulating end piece, the opposite end of said body 40 having an inwardly projecting flange, a coupling member rotatably connected to said flange, a weather shielding flange on said body extending over the joint between said coupling and its seat, and said weather 45 shielding flange being provided with a drain opening.

In testimony whereof I affix my signature.

FREDERICK I. JOHNSON.
